MOUNTING AND LET-OFF FOR BEAMS OF LOOMS

Filed Oct. 24, 1929

2 Sheets-Sheet 2

UNITED STATES PATENT OFFICE

RUDOLPH KRENZ, OF BUFFALO, NEW YORK, ASSIGNOR TO BUFFALO WEAVING AND BELTING COMPANY, OF BUFFALO, NEW YORK, A CORPORATION OF NEW YORK

MOUNTING AND LET OFF FOR BEAMS OF LOOMS

Application filed October 24, 1929. Serial No. 402,040.

This invention relates to a mounting and let off for the beams of looms or the like and more particularly to a means for supporting the warp beams upon the beam rack of a loom and a let off for each beam which is regulated by the tension of the warp thread and permits the beam to pay off when the warp thread is drawn taut but applies a brake to the beam when the tension is released. By 5 this means the warp threads are held at a constant tension which is requisite in weaving.

One of the principal objects of this invention is to provide a mounting for beams upon 15 a beam rack which permits the ready removal and replacement of the beams thereon and which reliably holds the beams upon the beam rack while the loom is in operation.

A further aim is to provide such a mounting 20 in which the beam supporting members are adjustable upon the beam rack so that they can be moved closer together or farther apart as the size of the beams may require, and also to provide such beam supporting 25 members, each of which is arranged to support the opposing ends of the axles of two adjacent beams, thereby reducing the number of such supports and providing a more compact beam rack.

Another object is to provide a simple and 30 effective brake for each beam, each of which brakes is responsive to the tension of the warp thread being payed out by the beam and operates to release the beam when a predetermined tension is applied to the warp, and 35 to stop the beam when the tension is released. By this means the beam is prevented from overrunning and a constant tension on each warp thread is maintained.

A further object is to provide such an independent individual brake mechanism for each beam in which the brake mechanisms are supported on slides which permit their ready 40 adjustment to the associated beam and in which the brake mechanisms are so mounted as to be readily removable from the beam rack.

Another purpose is to provide such an individual brake for each beam which is simple 45 in construction and has but few moving parts

and will operate reliably and continuously to maintain the desired tension on the warp threads.

Another aim is to provide such a structure 55 in which the counterbalancing weights are arranged out of the way and do not interfere with the free access to the beams upon the beam rack.

In the accompanying drawings:

Figure 1 is a fragmentary rear elevation 60 of a beam rack having beams mounted thereon in accordance with my invention.

Figure 2 is a side elevation thereof.

Figure 3 is an enlarged perspective view 65 of a beam supported on a beam rack in accordance with my invention.

Figure 4 is a fragmentary section taken on line 4-4 of Fig. 1.

Figure 5 is a top plan view of the braking mechanism associated with each beam. 70

Figure 6 is a vertical section taken on line 6-6 of Fig. 5.

Similar reference numerals refer to like parts in each view.

In its general organization this invention 75 comprises a beam rack composed of a plurality of spaced parallel bars, slides adjustably fixed on said bars and formed to provide half bearings receiving the axles of the beams, a pair of catches pivotally mounted on 80 each slide and retaining the beam axles in the half bearings, a second series of slides formed to provide half bearings and arranged between the beam supporting slides, and a brake mechanism removably carried in the half 85 bearings of the last named slides, each of said brake mechanisms acting on its associated beam and comprising a brake member or arm pivotally mounted between its ends, the rear end of said brake member being adapted to 90 engage the under side of said beam and the front end thereof having a rounded surface, a second arm or U-shaped member pivotally carried below the brake member the rear end of each U-shaped member being normally elevated by counterweights arranged at the top of the beam rack and the front end of each U-shaped member carrying a roller and a stationary arm projecting outwardly from 95 each of the brake mechanism carrying slides 100

and carrying rollers at their outer ends, the thread from each beam being threaded over said rounded part, under the roller carried by the U-shaped member, and over the stationary rollers whereby upon the application of a predetermined tension to said thread, the front end of said U-shaped member is raised and engages and raises the front end of the brake arm to release the beam.

10 The beam rack can be of any suitable form and is shown as consisting of a plurality of spaced parallel vertical bars 10 which are rectangular in cross section and are connected at their lower ends to a cross angle bar 11 and at their upper ends to a cross angle bar 12. The lower cross bar 11 can be supported in any suitable manner as on standards 13 and the upper cross angle bar 12 is connected to one or more longitudinal bars 14. These longitudinal bars 14 extend rearwardly and are secured at their rear ends to a suitable framework 15 and also carry a cross rod 16, this cross rod 16 carrying the counterweights for the several beam braking devices as herein-after described.

The beams 17 are mounted in the beam rack between the several vertical supporting bars, the beams being arranged in vertical and horizontal rows as indicated in Fig. 1.

30 The number of beams carried by the beam rack will depend, of course, on the size of the beam rack and the size of the beams, the number of beams depending upon the number of warp threads in the article being woven. 35 Each beam consists of a spool 18 on which a warp thread 19 is wound, and the spool is provided with an axle 20 which projects outwardly therefrom.

40 The supports 21 for the beams 17 are slidably mounted on the vertical bars 10 so as to be adjustable to different vertical positions thereon and for this purpose each support consists of a slide 22 having a vertical slide-way 23 extending therethrough which receives the vertical bar 10 and a set screw 24 which is arranged in the front side of the slide and engages the front edge of the bar 10. By this means the slide 22 is moved to its proper position and the set screw 24 tightened to hold it there.

45 On its rear side the slide 22 is formed to provide a rearwardly facing half bearing 25 the lower part of which is extended rearwardly to form a shaft 26. This half bearing also extends laterally outward from the sides of the slides and is adapted to receive the opposing ends of the axles 20 of two adjacent beams 17, as best shown in Fig. 1. In order to retain these axles in their half bearings, a pair of catches 27 are pivoted on opposite sides of the slides 22, the rear ends of these catches falling by gravity upon the shelf 26 in rear of the half bearing 25 so that the axles 20 of the beams cannot roll out of the bearings. The upward movement

of each catch is preferably limited by a stop pin 28. It is apparent that the horizontal rows of beams are vertically adjustable to suit the size of the beams by loosening the set screws 24 of the several slides 22 and moving the slides accordingly. Each slide 22 also supports the ends of two beams and each beam is also readily removed by lifting the two catches 27 which hold the opposite ends of its axle and moving the beam rearwardly from the rack.

50 Associated with each beam is an individual braking device which releases the beam upon the application of a predetermined tension on its warp thread and brakes the beam when this tension is released. Each of these braking devices is preferably constructed as follows:

55 Arranged below each of the slides 22 which carry the axles of the beam 17 is a second slide 29 which fits around the corresponding vertical bar 10 in the same manner as the slides 22 and is held in position thereon by a set screw 30 on its rear side. Each of these slides 29 carries a forwardly extending arm 31 which is preferably formed integrally with the slide and at their front ends these arms 31 carry a cross rod 32, the cross rod extending the full width of the beam rack. Each slide 29 is also formed on its opposite sides to provide forwardly facing half bearings 33 and the shafts 34 carried by these half bearings are held in position by pins 35, as best shown in Fig. 4. These shafts 34 extend between the opposing half bearings of two corresponding slides 29 and each shaft is disposed immediately below one of the beams 17.

60 On this shaft is the brake member or arm which acts upon the beam above the same. This brake member or arm includes a pair of bearings 36 on the shaft 34 and from these bearings 36, arms 37 project forwardly. The front ends of these arms 37 are connected by an integrally formed cross piece 38 which is preferably rounded so that the warp thread 19 rides around the same freely. The warp thread is kept from riding off this rounded part 38 by a pair of pins 39. One of the bearings 36 is also formed to provide a short rearwardly projecting arm 40 which is arranged in close proximity to the periphery or adjacent side flange of the beam and is provided with a slot in which is arranged a piece of steel 41 or the like. This steel is arranged to be moved into contact with the beam and brake its movement.

65 The bearings 36 are also formed to provide hangers or depending arms 42 which carry a second cross rod 43. On this rod a U-shaped horizontal bracket or arm 44 is mounted for rocking movement, this bracket or arm preferably consisting of a cross piece 45 and integrally formed arms or legs 46 which are mounted intermediate their end on the cross

rod 43 and at their front ends carry a cross roller 47. This roller can be mounted on a cross pin 48 or in any other suitable manner. Between each of the stationary arms 31, a similar roller 49 is mounted on the cross rod 32 which, as previously described, runs the full width of the beam rack. The arms or legs 46 of the rocking bracket or arm 44 also are formed at their front ends to provide shoulders 50 which, when the front end of the bracket 44 is rocked upwardly, engage the under sides of the arms 37 of the brake to release the brake.

Suitably attached to the rear ends of each of the brackets 44 is a counterweight rod 51. This rod can be attached to a screw 52 on either side of the bracket, as shown in Fig. 3, or as shown in the case of the central beam in Figs. 1 and 2, it can be bent around the cross piece 45 of the bracket. Each of these counterweight rods extends upwardly and is connected to the rear end of a separate rock lever 53, these rock levers 53 being carried by the upper cross rod 16. A counterweight holder 54 is secured to the opposite end of each of these rock arms 53 and on this holder a suitable number of removable counterweights 55 are removably carried. By the provision of a separate rod 51, rock lever 53 and counterweight 55 for each beam brake mechanism, each operates entirely independent of the others and independently maintains the tension on each thread.

With a beam rack, beams and braking mechanism therefor as above described, the warp thread from each beam is passed over the rounded front end 38 of the brake member or arm associated with it, under the corresponding roller 47, over the stationary roller 49 and thence passes to the loom in any suitable manner. When there is no great tension on the warp thread, the counterweights 55, through the rock lever 53 and counterweight rod 51 holds the rear end of the bracket or arm 44 elevated and the front end thereof depressed. In this position, the preponderating brake member or arm holds the rear end or arm 40 thereof elevated and in engagement with the beam, thereby holding the beam against movement. When, however, a tension is applied to the warp thread 19 sufficient to overcome the counterweights 55, the thread, passing under the roller 47, elevates the front end of the U-shaped member or arm 44 and moves its shoulder 50 into engagement with the front end of the brake member. This upward movement of the brake member depresses its rear end or arm 40, thereby releasing the beam and permitting the warp thread to let off. As soon as the tension on the warp thread is released, the counterweights 55 again restore the brake to its normal braking or operative condition.

It is apparent that this let off device is very sensitive and will maintain a predeter-

mined tension on the warp thread of each beam at all times, and at the same time consists of few parts which are not likely to get out of order so that the braking device will function properly for a long time. Both the braking mechanisms and the beams are also readily removed from the rack and interfering parts are reduced to a minimum, the counterweights 55, in particular, being suspended in a position where they are out of the way.

Both the beams and the braking mechanisms are also mounted so as to be adjustably positioned on the beam rack as conditions may require and all the parts are interchangeable, thereby reducing the cost of manufacturing beam racks of this character.

Having described my invention, I claim:

1. A device of the character described comprising a beam rack including spaced parallel members, slides provided on said parallel members, means for securing said slides in any adjusted position, said slides being formed on their opposite sides to provide rearwardly facing half bearings adapted to receive the opposing ends of the axles of two beams, a catch pivoted on each side of each slide and having a hook shaped end adapted to be arranged in rear of each half bearing and retain the axles of the beams therein.

2. A device of the character described, comprising a beam rack, a plurality of beams rotatably supported on said beam rack, an upper stationary arm projecting forwardly from said beam rack adjacent each beam, a roller carried at the front end of said stationary arm, a brake lever pivoted at its center below each beam to a stationary part, the rear end of said brake lever being adapted to engage the under side of its associated beam and the front end thereof being formed to provide a rounded surface, a second arm pivoted at its center below the pivotal mounting of said brake lever, the front end of said second arm being movable upwardly into engagement with said brake lever to apply the brake lever to its beam, a roller carried at the front end of said second arm and gravity means for normally depressing the front end of said second arm, the thread from said beam first passing over said rounded surface, then under the roller on said second arm, and thence over said roller on said stationary arm whereby upon the application of a predetermined tension to said thread said brake lever is released from said beam.

3. A device of the character described, comprising a beam rack including a plurality of spaced vertical bars, a plurality of beams rotatably mounted in rows between said bars, a brake member pivotally carried by said bars below each beam, said brake member comprising an arm projecting rearwardly from its pivotal mounting and adapted to engage the

under side of said beam, a part projecting forwardly therefrom and a horizontal rounded part at the front end of said brake member, a U-shaped member having forwardly 5 projecting legs pivotally mounted on said vertical bars below said brake member, a roller carried between the ends of said legs and arranged immediately below the rounded part of said brake member, a stationary arm projecting forwardly from said vertical bars, a stationary roller arranged on said stationary arm above the roller on said U-shaped member, a counterweight rod extending upwardly from the rear end of each U-shaped member, 15 and a counterweight for each counterweight rod, said counterweight being suspended at the upper end of said beam rack and yieldingly elevating the rear end of said U-shaped part, said counterweighted U-shaped part 20 normally permitting the front end of said brake member to be depressed whereby said brake arm is applied to said beam and the thread from said beam passing over said rounded part, under the roller of said U-shaped part and over said stationary roller whereby upon application of a predetermined tension to said thread, the front end of said U-shaped part is elevated and moves the front end of said brake member to release said brake 25 arm.

4. A device of the character described, comprising a beam rack, a plurality of beams rotatably supported in rows on said beam rack, a brake mechanism arranged adjacent 35 each beam and acting thereon, gravity means for yieldingly holding each brake mechanism in engagement with the associated beam comprising a counterweight rod connected to each brake mechanism, a plurality of rock levers pivoted at their centers at the upper part 40 of said beam rack, one end of each counterweight rod being connected to one end of a corresponding rock lever and a counterweight suspended from the opposite end of each lever, and means connecting the thread of each beam with the associated brake mechanism whereby upon the application of a predetermined tension to said thread, said brake is released.

5. A device of the character described, including a beam rack composed of a plurality of spaced parallel bars, slides carried by said bars and adapted to rotatably support the beams between said bars, a second series of 55 slides arranged between said beam supporting slides, a plurality of brake mechanisms carried by said second slides, each of said brake mechanisms acting on an associated beam to maintain a tension on the thread 60 thereof and means for securing said slides in any adjusted position along the said bars.

6. A device of the character described, including a beam rack composed of a plurality of spaced parallel bars, slides carried by said 65 bars and adapted to rotatably support the

beams between said bars, a second series of slides arranged between said beam supporting slides, each of said second slides being formed to provide a half bearing, a plurality of brake mechanisms pivotally supported in 70 said half bearings and removable therefrom, each of said brake mechanisms acting on an associated beam to maintain a tension on the thread thereof and means for securing said slides in any adjusted position along said 75 bars.

In testimony whereof I affix my signature.
RUDOLPH KRENZ.
